COMBINED TABLE AND SEATING UNIT

Henry Soszynski, 274 King St., Hanson, Mass.

Filed Feb. 19, 1963, Ser. No. 73,630

Term of patent 14 years

(Cl. D33—14)

Fig. 1.

Fig. 2.

Fig. 3.

I claim:

The ornamental design for a combined table and seating unit, as shown.
